UNITED STATES PATENT OFFICE.

WILLIAM E. VAN VELSOR, OF PHILADELPHIA, PENNSYLVANIA.

IMPROVEMENT IN PILL-TILES.

Specification forming part of Letters Patent No. **163,552**, dated May 18, 1875; application filed April 14, 1875.

To all whom it may concern:

Be it known that I, WILLIAM E. VAN VELSOR, of the city and county of Philadelphia, in the State of Pennsylvania, have invented an Improvement in Pill-Tiles, of which the following is a specification:

My invention consists of a glass pill-tile having a ground surface to prevent the slipping of the pill mass, as hereinafter described.

The accompanying drawing is a face view of the pill-tile, which has a ground face, as represented. This grinding of the face is performed on a revolving flat stone, the tile being

shifted around to change its position to produce a regular surface, by which the pill mass is prevented slipping when rolled. The tile is provided with a scale, in the usual manner, to be used in cutting the pills to their proper size.

I claim as my invention—

As an article of manufacture, a pill-tile of ground glass.

WILLIAM E. VAN VELSOR.
